(Cl. D54—14)

To all whom it may concern:

Be it known that I, Eugene J. Majewski, a citizen of the United States, residing at Chicago, in the county of Cook and State of Illinois, have invented a new, original, and ornamental Design for a Portable Drill Unit, of which the following is a specification, reference being made to the accompanying drawings, forming a part hereof.

In the drawings:

Fig. 1 is a front perspective view of a portable drill unit showing my new design;

Fig. 2 is a side elevational view thereof;

Fig. 3 is a top plan view thereof;

Fig. 4 is a front end elevational view thereof;
and

Fig. 5 is a rear end elevational view.

I claim:

The ornamental design for a portable drill unit,
substantially as shown.

EUGENE J. MAJEWSKI.
